BENJAMIN F. CADY, OF CHITTENANGO, NEW YORK.

Letters Patent No. 82,380, dated September 22, 1868.

IMPROVEMENT IN SLED-KNEES.

The Schedule referred to in these Letters Patent and making part of the same.

TO ALL WHOM IT MAY CONCERN:

Be it known that I, BENJAMIN F. CADY, of Chittenango, in the county of Madison, and State of New York, have invented a new and valuable Improvement in Sleigh-Knees; and I do hereby declare that the following is a full, clear, and exact description of the construction and operation of the same, reference being had to the annexed drawings, making a part of this specification, and to the letters and figures of reference marked thereon.

The object of my invention is to construct a sleigh-knee that shall be more simple in construction and more permanently useful than any similar device heretofore known.

To this end, I first construct a rod of malleable or wrought iron, in the form shown by the letter A of the drawings. The lower end of this rod passes through and is made fast to the sleigh-runner, and the upper end passes through the top cross-piece and bottom board of the sleigh-body. The sleigh-runner is represented by the letter B, the top cross-piece by C, and the bottom board by D, on the drawings.

At the top of the bottom board, I cut a thread on the rod A, and adjust to it a nut, as shown. This thread and nut are shown at E. The lower end of rod A is made fast in the sleigh-runner by means of a head, G, bearing upward against a shoulder in said runner.

It will readily be perceived that by means of said head G and the nut and screw E, the operator can tighten the rod at will, and may remove it altogether with great ease.

In order to protect said rod A, to give additional strength to the same, and furnish suitable bearings for the runner and cross-piece, I construct a shield, marked H on the drawings, which fully insures to the knee all the benefits named. The flanches *a a* clasp the upper side of the runner, and the flanches *c c* clasp the lower side of the cross-piece. At the point O, I leave an opening in the shield, for the insertion of a screw, by means of which the shield is always held firmly, and prevented from either a forward or backward movement under the cross-piece. For the purpose of cheap and rapid manufacture, I usually construct the shield H of cast iron.

What I claim as my invention, and desire to secure by Letters Patent, is—

A sleigh-knee having rod A and shield H, constructed, combined, and arranged, substantially as described, as a new article of manufacture.
